R. R. NORWOOD

SUSPENDERS

Filed Aug. 6, 1927.

UNITED STATES PATENT OFFICE.

ROBERT R. NORWOOD, OF MINERAL WELLS, TEXAS.

SUSPENDERS.

Application filed August 6, 1927. Serial No. 211,185.

This invention aims to provide a novel pair of suspenders, adapted to be worn under a shirt, with the shirt extended inside of the trousers, the construction being such that a double point of connection between the suspenders and the trousers is provided at each side of the trousers. Another object of the invention is so to construct the device that the trousers will be supported evenly at the front and at the back, and will neither be pulled up unduly, or be permitted to sag to an objectionable extent, either at the front or at the back.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:—

Figure 1 shows in perspective, a pair of suspenders constructed in accordance with the invention, parts being broken away;

Figure 2 is a section on the line 2—2 of Figure 1;

Figure 3 is a fragmental perspective showing a modification.

The suspenders forming the subject matter of this application may be made of elastic or inelastic material, as the manufacturer may desire. The article includes a pair of straps 1 including rear arms 2 and forward arms 3, the rear arms 2 being crossed loosely and freely upon each other, as shown at 4. A slide 5 is provided, through which the rear arms 2 pass freely at their point 4 of crossing. The slide preferably consists of outer strips 6 and an intermediate strip 7 between the outer strips 6, the ends of the strips 6 and 7 being connected, as shown at 8. Each of the arms 2 passes through be-

tween the intermediate strip 7 and one of the outer strips 6, the intermediate strip 7 being located between the arms 2, as shown in Figure 2, the arms, thus, being prevented from rubbing on each other. The lower ends 55 of the forward arms 3 are fashioned into loops 9 which are held at adjusted lengths by buckles 10.

There are eyes 11 at the lower ends of the rear arms 2, and in the loops 9. With the 60 eyes 11 are connected depended tabs 12 carrying at their lower ends, loops 14 or any other suitable means for engaging a pair of trousers. Circumferential ties 15 connect the tabs 12. The tabs 12 at the front of the 65 suspenders have extensions 16 provided with any suitable devices 17 for holding stockings or socks. It will be understood that the parts 16 may be omitted if desired.

The device is so constructed that there is 70 a two-point connection with the trousers at each side of the trousers, this construction resulting owing to the presence of the loops 14, which are disposed in pairs at the sides of the suspenders, as clearly shown in Figure 75 1 of the drawings. The ties 15 hold the loops 14 of the pairs in proper relation to each other, and serve to distribute the upward pull on the trousers.

In Figure 3, parts hereinbefore described 80 have been designated by numerals previously used, with the suffix "a". In this form of the invention, the ties 15^a are made, each, in two pieces, connected by a buckle 18, to the end that the ties 15^a may be adjusted as 85 to length.

What is claimed is:—

A pair of suspenders made up of straps including rear arms and forward arms, the rear arms being crossed, means for connecting the rear arms together loosely and freely for relative sliding movement at their place of crossing, the forward arms being fashioned into adjustable loops, means for holding each loop at an adjusted length, front 90 breeches-engaging members carried by the loops, the space between the front breeches-engaging members being open, rear breeches-engaging members directly connected to the rear arms, the space between the rear 95 100

breeches-engaging members being open, circumferential ties permanently secured at their extreme ends to the front and rear breeches-engaging members, and means interposed in the ties for holding them adjustably at a fixed length, thereby to determine a fixed maximum distance between the front

breeches-engaging member, and one rear breeches-engaging member.

In testimony that I claim the foregoing ¹⁰ as my own, I have hereto affixed my signature.

ROBT. R. NORWOOD.
